UNITED STATES PATENT OFFICE.

GEORGE B. BASSETT, OF BUFFALO, NEW YORK.

DESIGN FOR A CYCLOMETER-CASE.

SPECIFICATION forming part of Design No. 27,544, dated August 17, 1897.

Application filed June 28, 1897. Serial No. 642,760. Term of patent 14 years.

To all whom it may concern:

Be it known that I, GEORGE B. BASSETT, a citizen of the United States, residing at Buffalo, in the county of Erie and State of New York, have invented and produced a new and original Design for Cases for Supporting the Working Parts of Cyclometers, Odometers, and Similar Instruments or Counting-Machines, of which the following is a specification, reference being had to the accompanying drawings, forming a part thereof.

Figure 1 is a perspective view of a case which embodies my new design. Fig. 2 is a side elevation of the case shown in Fig. 1, and Fig. 3 is an end elevation thereof.

As shown in the drawings, the leading or material feature of my design consists of forming the case with the cross-section and ends of an elongated curved contour or horseshoe shape.

A is the case, which has a cross-section of an elongated curved contour or horseshoe shape and longitudinal and horizontal sections of a rectangular form.

B is a sight-opening, and C and C' are two projections formed on the sides of case A as a convenient means of supporting it in a clamp or otherwise.

Having described my invention, what I claim as new, and desire to secure by Letters Patent, is—

The design for a cyclometer-case substantially as shown and described.

GEORGE B. BASSETT.
